UNITED STATES PATENT OFFICE.

JOSEPH SPEKTORSKY, OF NEW YORK, N. Y.

DESIGN FOR A FEATHER-DUSTER HANDLE.

SPECIFICATION forming part of Design No. 27,295, dated July 6, 1897.

Application filed May 29, 1897. Serial No. 638,816. Term of patent 7 years.

To all whom it may concern:

Be it known that I, JOSEPH SPEKTORSKY, a citizen of the United States, residing at New York, in the county of New York and State of New York, have invented a new and original Design for Feather-Duster Handles, of which the following is a full, clear, and exact specification, reference being had to the accompanying drawing, which forms a part thereof.

The drawing forming part of this specification represents a side view of my design, one view being deemed sufficient to fully illustrate the same.

15 The chief feature of my design consists of a plurality of conical sections A, formed on the handle B, the outer section being so formed as to represent the frustum of a cone and the smaller ends of each of said sections 20 being directed outwardly, and the sections A are also separated by an annular groove whereby a neck-shaped portion C is formed.

Between the handle proper and the inner cone-shaped section A are two sections D and 25 E, which are substantially cylindrical in form and which are separated by annular beads F, and between the section E and the handle proper are other annular beads G.

The section D is slightly larger than the 30 section E and is also slightly larger at the outer than at the inner end, and the inner end is beveled, and between the section D and the inner conical section A is a groove

whereby a neck-shaped portion C is formed similar to those between the conical sections A. 35

The conical sections A gradually decrease in size outwardly and are intended to receive the feathers of the duster or to have the same secured thereto, and though I have shown 40 three of the conical sections A it will be apparent that a different number may be employed without materially changing the design, the principal feature of which consists of a plurality of conical sections formed on 45 the end of a handle, the smaller ends of which are directed outwardly, and a second chief feature of the design consists in the fact that said conical sections decrease in diameter outwardly, and in the further fact that between 50 each of said sections are neck-shaped portions formed by annular grooves.

Having fully described my new and original design, I claim as new and desire to secure by Letters Patent—

55 The design for duster-handles herein described.

In testimony that I claim the foregoing as my invention I have signed my name, in presence of the subscribing witnesses, this 26th 60 day of May, 1897.

JOSEPH SPEKTORSKY.
